COLLAPSIBLE CELLULAR PARTITION FOR
CONTAINERS

Walter C. George, St. Louis, Mo., assignor to
Gaylord Container Corporation, St. Louis, Mo.,
a corporation of Maryland

Application September 15, 1947, Serial No. 774,019

7 Claims. (Cl. 229—42)

1

This invention relates to collapsible cellular strip type partitions for containers, particularly bottle cartons.

The invention has for its principal object to provide a partition of the above type that is strong and durable, simple and economical and may be quickly and easily permanently assembled in collapsed flat compact form for shipment or storage and readily set up for use. Other objects are to provide for permanently securing the partition strips together without the use of stitching or mechanical fasteners, to provide for horizontal ventilation through the bottle cells and for cushioning the bottles therein. The invention consists in the collapsible strip-type cellular bottle carton partition and in the construction, combinations and arrangements of parts hereinafter described and claimed.

In the accompanying drawings, which form part of this specification and wherein like symbols refer to like parts wherever they occur,

Fig. 1 is a plan view of the eight partition strips from which a twenty-four bottle cell partition embodying my invention is made, the strips being shown in the longitudinal positions and in top-to-bottom order which they occupy in the assembled partition.

Fig. 2 is a plan view of the partition in open or set-up position.

Fig. 3 is a side elevational view of the set-up partition.

Fig. 4 is an end elevational view of the set-up partition.

Fig. 5 is a vertical cross-sectional view on the line 5—5 in Fig. 2.

Fig. 6 is a vertical longitudinal sectional view on the line 6—6 in Fig. 2.

Figs. 7 and 8 are fragmentary horizontal cross-sectional views on the lines 7—7 and 8—8, respectively, in Fig. 3.

Figs. 9 and 10 are plan views looking at opposite sides of the collapsed partition.

Fig. 11 is a side edge elevational view of the collapsed partition shown in Fig. 10.

Fig. 12 is a plan view showing the partition partially opened.

Fig. 13 is a fragmentary horizontal cross-sectional view similar to Fig. 8 through a partition of a modified form.

Fig. 14 is a vertical sectional view on the line 14—14 in Fig. 13; and

Fig. 15 is a fragmentary sectional view of the partition shown in Fig. 13 and 14, showing the manner in which the bottle cushioning bosses of adjacent partition strip panels seat one within

another in the fully collapsed position of said partition.

My collapsible cellular bottle separating partition is made of eight partition strips of corrugated board, fiberboard or other bendable material; namely, two counterpart strips A, two counterpart strips B, two counterpart strips C and two counterpart strips D, said strips increasing in length from the strips A to the strips D. All of the partition strips are provided with one or more substantially S-shaped cross slits 1 and cut scores 2 extending from the ends of said slits to the side marginal edges thereof, thereby forming counterpart end panels 3 on all of said strips and two or more intermediate panels 4 on the strips B, C and D depending on the length thereof. The reverse loops at the ends of the S-shaped slits 1 form at the inner ends of scores 2 notches 5 with tongues 6 snugly fitting therein. As shown in Figs. 1, 9 and 10, the end panels 3 of all of the strips have a notch 5 and a tongue 6 at their inner edges that are spaced apart transversely of said strips; and the intermediate panels 4 have similarly arranged notches and tongues along two opposite edges. The number of intermediate panels 4 increases with the increased length of the strips. For a twenty-four bottle partition, the strips B are provided with two intermediate panels, the strips C with four intermediate panels and the strips D with five intermediate panels.

As shown in Fig. 9, 10 and 11, the above strips are stacked or laid flatwise one on another with the two strips A located one at the top and the other at the bottom. The two strips B are located one next to each strip A, the two strips C are located one next to each strip B, and the two strips D are located next to one another and between the two strips C. The strips are offset longitudinally in the stack in the manner shown in Figs. 1, 9, 10 and 11 with their transverse score lines in register vertically. As shown in Fig. 1, the strips of each pair A, B, C and D are reversed so that the corresponding tongues of adjacent strips extend in opposite directions. With the strips thus arranged, the tongues 6 of each strip are adhesively or otherwise permanently secured flatwise to the strip or strips in contact therewith, the tongues of each of the intermediate strips B, C and D being secured in alternation lengthwise first to one and then to the other of the two strips in contact with opposite sides thereof.

The collapsed strip type partition above described is adapted to be opened or set up to form a twenty-four cell bottle partition by pulling in opposite directions on the two outermost strips

A until all of the strips are bent at right angles along each of the score lines thereof, the longer strips B, C and D being bent in zigzag fashion. The strips when bent into such position form three-sided bottle cells or compartments around the four sides of the partition and four-sided cells or compartments within the space bounded by the open-sided marginal cells or compartments. In the set-up position of the collapsible partition, the tongues 6 of all of the strips are not bent but remain in their original planes; that is, in the plane of the body of the strip. Two vertically spaced tongues are located at each corner of each bottle cell or compartment and extend straight from one compartment into another through the notches 5 vacated by the tongues when the strips are bent along the score lines into compartment-forming position.

In the construction shown in Figs. 13, 14 and 15, the cell or compartment-forming panels of the strips are provided with vertical rows of hollow bottle cushioning bosses 1 arranged in two alternating series from top to bottom of the partition, the bosses of one series projecting on one side of the panels and the bosses of the other series projecting on the other sides thereof. The bosses 1 are pressed in the panels from opposite sides thereof and are of the same size and shape so that when the partition is collapsed the bosses of each panel will enter the bosses of the adjacent panel in contact therewith, thereby permitting the superimposed strips of the collapsed partition to seat directly one on the other without any space therebetween.

The hereinbefore described collapsible cellular bottle partition has many important advantages. It is simple and inexpensive and can be readily assembled into compact collapsed form for shipment or storage. The partition may be readily erected merely by pulling endwise in opposite directions on the two outermost strips A, all of the strips being readily bendable along the score lines thereof. The tongues of each strip are permanently secured flatwise to the strips in contact therewith and lie stiff and straight in the planes of the panels from which they extend and against the panels to which they are connected when the partition is erected, thereby increasing the strength and rigidity of the erected partition and preventing the strips from curling or bowing. The construction provides reinforcing, stiffening and connecting tongues at the top and bottom of each corner of each cell or compartment in the set-up partition and the openings formed in the panels by the tongues struck therefrom provide both longitudinal and cross ventilation through the set-up partition. The bosses formed in the panels which form the side walls of the bottle cells or compartments serve as cushions to prevent breakage of the bottles and the nesting of these hollow bosses in the collapsed partition enables the strips to lie flatwise against each other and thus hold the thickness of the collapsed partition to a minimum. Another advantage of the present construction is that the S-shaped tongue and ventilating opening forming slits are mere cuts instead of slots and thus do not produce paper dust which tends to settle in the bottles when they are placed in the compartments of the partition for filling.

Obviously, the hereinbefore described bottle partition admits of considerable modification without departing from the invention. Therefore, I do not wish to be limited to the precise construction shown and described.

What I claim is:

1. A collapsible cellular partition for containers comprising a plurality of superimposed partition strips provided with cross slits and score lines extending from the ends of said slits to the side marginal edges of said strips, said slits and score lines dividing the said strips into a series of cross panels, the slits of each strip being shaped to form tongues in the plane thereof projecting from the adjacent edges of the panels thereof, the tongues of each strip being permanently secured flatwise to adjacent panels of the strip or strips in contact therewith, the collapsed partition being adapted to be set up by bending the strips along their score lines to bring their panels into cell forming relation, said tongues being located at the corners of the cells in the set-up position of said partition with the tongue of each cell forming panel extending straight from the cell formed in part thereby into an adjacent cell.

2. A collapsible cellular partition for containers comprising a plurality of superimposed partition strips provided with substantially S-shaped cross slits and score lines extending from the ends of said slits to the side marginal edges of said strips, said slits and score lines dividing the said strips into cross panels with tongues projecting from the adjacent edges thereof in planes thereof, the tongues of the panels of each strip being permanently secured flatwise to adjacent panels of the strip or strips in contact therewith, the collapsed partition being adapted to be set up by bending said strips along their score lines to bring their panels into cell forming relation, said tongues being located adjacent to the corners of said cells and being disposed in the planes of the panels from which they project in both collapsed and set-up positions of said partition.

3. A collapsible cellular partition for containers comprising a plurality of superimposed partition strips provided with substantially S-shaped cross slits and score lines extending from the ends of said slits to the side marginal edges of said strips, said slits and score lines dividing said strips into cross panels with tongues and notches along the adjacent edges thereof in the planes thereof, the tongues of the panels of each strip being permanently secured flatwise to adjacent panels of the strip or strips in contact therewith, the collapsible partition being adapted to be set up by bending said strips substantially at right angles along their transverse score lines to bring the panels into cell forming relation, said tongues being located adjacent to the corners of the cells in the set-up position of said partition and extending through said notches in said position from one cell to an adjacent cell.

4. A collapsible cellular partition for containers comprising a plurality of superimposed partition strips provided with substantially S-shaped cross slits and score lines extending from the ends of said slits to the side marginal edges of said strips, said slits and score lines dividing said strips into cross panels with tongues and notches along the adjacent edges thereof in the planes thereof, the tongues of the panels of each strip being permanently secured flatwise to adjacent panels of the strip or strips in contact therewith, the collapsible partition being adapted to be set up by bending said strips substantially at right angles along their longitudinal score lines to bring the panels into cell forming relation, said tongues being located adjacent to the corners of the cells in the set-up position of said partition and extending through said notches in said

position from one cell to an adjacent cell, said tongues lying in the planes of the panels from which they extend in both collapsed and set-up positions of said partition.

5. A collapsible cellular partition for containers comprising a plurality of superimposed strips provided with cross slits and score lines extending from the ends of said slits to the side marginal edges of said strips, said slits and score lines dividing said strips into a plurality of cross panels, the slits of said strips being shaped to form tongues one along each of the two adjacent edges of the panels thereof, the tongues of each strip being permanently secured flatwise to the strip or strips in contact therewith, the collapsed partition being adapted to be set up by bending the strips along their score lines to bring their panels into cell forming relation with each panel forming one complete side of a cell, said panels having vertical rows of outstanding cushioning bosses on opposite side faces thereof.

6. A collapsible cellular partition for containers comprising a plurality of superimposed strips provided with cross slits and score lines extending from the ends of said slits to the side marginal edges of said strips, said slits and score lines dividing said strips into a plurality of cross panels, the slits of said strips being shaped to form tongues one along each of the two adjacent edges of the panels thereof, the tongues of each strip being permanently secured flatwise to the strip or strips in contact therewith, the collapsed partition being adapted to be set up by bending the strips along their score lines to bring their panels into cell forming relation with each panel forming one complete side of a cell, said panels having outstanding cushioning portions on opposite

side faces thereof, said cushioning portions comprising vertical rows of hollow hemispherical bosses pressed in said panels from opposite sides thereof and adapted to be brought into nested relation in the collapsed position of said partition.

7. A collapsible cellular partition for containers comprising a plurality of superimposed partition strips divided into a plurality of cross panels and connected together so that the partition may be collapsed or opened into cell forming position, said panels having outstanding cushioning portions on opposite side faces thereof, said cushioning portions comprising vertical rows of hollow bosses pressed in said panels from opposite sides thereof and adapted to be brought into nested relation in the collapsed position of said partition, said bosses being arranged in two alternating series from top to bottom of said partition with the bosses of one series projecting on one side of the panels and the bosses of the other series projecting on the other side thereof.
